OF ONE-THIRD TO CHARLES H. CORNELL, OF VALENTINE, NEBRASKA.

SOLDERING-IRON.

1,097,518.

Specification of Letters Patent.

Patented May 19, 1914.

Application filed June 14, 1913. Serial No. 773,680.

To all whom it may concern:

Be it known that we, LEONARD L. BIVENS and GEORGE G. HUNTER, citizens of the United States, residing at Valentine, in the 5 county of Cherry and State of Nebraska, have invented certain new and useful Improvements in Soldering-Irons; and we do hereby declare the following to be a full, clear, and exact description of the invention, such as will enable others skilled in the art to which it appertains to make and use the same.

This invention is a soldering iron or copper and has for its object to provide a 15 burner for effecting a more complete combustion of fuel with a consequent better heating effect by the use of any suitable gas under pressure.

A further purpose of this invention is to 20 provide the operator with irons of various sizes and shapes, suitably proportioned to the work in hand, that may readily be substituted for the one in use on the burner without danger to the hands of the operator 25 from the heated iron.

Another object is to provide a plurality of mixing chambers to increase the heating capacity with a consequent saving in fuel.

With these ends in view, the invention 30 consists of an interchangeable copper or iron having a combustion and mixing chamber, suitable connecting means for engaging a handle of non-conducting material, a burner provided with a mixing chamber and adapt- 35 ed for engagement with a plurality of different irons, said burner coöperating with said handle, and means for conveying gas to the burner.

One embodiment of the invention is shown 40 in the accompanying drawings, in which—

Figure 1 is a side view. Fig. 2 is a trans- 45 verse section on the line 2—2 of Fig. 1. Fig. 3 is a longitudinal sectional view. Fig. 4 is a side elevation of the burner. Fig. 5 is an end view of the iron.

The soldering iron or copper A is pro- 50 vided with a plurality of transverse ports of varying diameters B, connecting with the mixing and combustion chamber C, to carry off the products of combustion, and 55 supplying additional air to be heated and consumed. These apertures decrease in size as they approach the working end of the iron. By making these ports of various sizes, it prevents the flame from being

chilled and its temperature lowered as well as preventing an undue chilling of the iron, by the introduction of too much cold air, the smaller ports retaining the heated air and allowing it to escape slowly and gradually 60 that it may give up its heat units, without creating a draft. The walls are heated by this method by conduction convection and radiation, and to a great extent the eddy currents, produced by the entering cold air 65 to the mixing and combustion chamber, are prevented, enabling the iron to be more thoroughly heated at the point thereof. At the inner end of the iron A is an aperture D, substantially centrally located which at 70 its outer end is preferably cone-shaped and which communicates with the mixing and combustion chamber C. Arranged around, and adjacent to, aperture D are air inlet ports E. The air inlet ports E terminate 75 within the chamber C at a point beyond the seat of the burner nozzle F, which is preferably of a truncated cone shape and adapted to engage with a seat within the aperture D, making a substantially air and gas tight 80 joint. The air ports E admit air to the flame at a point where it produces the maximum amount of heat and consequently using less gas. These ports E, communicating with the chamber C, are preferably angularly displaced with reference to the longitudinal axis of the iron A, so that the entering air has the same relative direction of flow as the gas.

The iron A is provided with an arm or 90 arms G, said arms being suitably connected in a permanent manner to the iron A, and to the tapered sleeve H. The sleeve H may be rigidly connected with the handle I, by any suitable means. One means is shown 95 by the screw J, to prevent the sleeve H, carrying the iron A, from revolving or moving during the operation of soldering, and to keep the burner nozzle F in engagement with its seat D. The employment of such 100 means allows interchangeability of different sizes of irons, whereby the tool may be adapted to light or heavy work, as the occasion may require, and is for all purposes a solidly handled soldering iron.

The sleeve H may be made of any suitable material.

The handle I is, preferably, made of suitable material, such as wood, having centrally located, through its longitudinal axis, 110

a hole K, adapted to receive a gas tight tube L, which is provided with suitable means at its outer end for connection with a gas supply, to convey gas to the mixing chamber r in the member M of the burner, located 5 upon the inner end thereof.

The burner comprises a mixing chamber r in the member M, preferably of larger diameter than the gas supply tube L. This 10 burner is preferably secured to the tube L by a suitable coupling S. The member M is shown in Fig. 3 provided with a threaded end m and with an inner reduced portion n forming a small nozzle at q, whereby gas 15 under pressure is admitted to a chamber r into which leads the inclined ports O. The air ports O are so positioned that the incoming gas draws air through them in the same relative direction as the gas flow, thereby 20 producing a more thorough mixture, consequently using the gas with greater economy and generating greater heat in the flame.

Projecting from the member M is a stem 25 P, carrying at its outer end the substantially truncated cone-shaped burner nozzle F, which engages with its seat D in the iron A. The nozzle F is provided with a centrally disposed opening which communicates directly with the mixing chamber r of the burner, and also with the mixing and combustion chamber C. It will be observed that a continuous passage is provided from the gas supply tube to the combustion chamber of the iron. Upon the gas supply tube 30 L may be located any suitable means, such as a stop cock (not shown) for controlling the supply of gas.

In operation, gas is admitted under pressure to the outer end of tube L, flowing 35 thence to the mixing chamber of the burner where it comes into contact with the air. The pressure of the gas draws air through the air inlet ports, and mixes it with the gas. The mixture then passes through the stem 45 P and through the opening in the burner nozzle into the mixing and combustion chamber C. Just beyond this nozzle F terminate additional air inlet ports E. The air 50 inlet ports supply additional air to the flame at its point of combustion and tend to produce an intense blue flame. The admission of air at the lower part of the flame to be gently blown over the combustion cone in 55 the same relative direction, produces a flame of intense heat with neither oxidation nor deoxidation. That is, the composition of the flame will be one that creates the greatest amount of heat, thereby materially changing 60 the character and quality of the flame. The products of combustion are carried off by the transverse ports which communicate with the mixing and combustion chamber, thereby providing more complete combustion.

It is obvious that the invention is not limited to the precise construction shown in the drawings, as various modifications and alterations may be made therein by one skilled in the art within the scope of the 70 appended claims.

Having thus fully described our invention, what we claim as new and desire to secure by Letters Patent is:

1. In a soldering tool, an interchangeable 75 iron provided with a central aperture, and a centrally disposed seat at one end thereof registering with said aperture, a burner provided with a tapered nozzle adapted to engage with said seat, arms connecting said 80 iron with a sleeve, and a handle connected to the burner.

2. A soldering tool, an iron comprising a combustion and mixing chamber and provided with arms extending in a longitudinal 85 direction, a sleeve rigidly connected to said arms, said iron being provided with transverse ports of varying diameters communicating with said mixing and combustion chamber, and provided, also, with a cone 90 shaped aperture at its lower end, a burner nozzle adapted to be seated in said aperture, and air inlet ports surrounding said aperture and terminating within the mixing and combustion chamber, at a point beyond the 95 burner nozzle.

3. In a soldering tool, a sleeve, an iron provided with a burner seat and a mixing and combustion chamber, transverse air ports 100 communicating with said chamber, arms rigidly connecting said iron to said sleeve, a handle, means for detachably securing the sleeve to said handle, and a burner comprising a mixing chamber, a stem projecting therefrom carrying a cone shaped burner 105 nozzle at one end for engaging said seat, and means to supply gas through said handle to the mixing chambers of said burner and soldering iron, and means to admit air to the top of the nozzle and into the mixing 110 chamber of the burner.

4. In a soldering tool, an iron, arms rigidly connecting said iron to a tapered sleeve, locking means carried by said sleeve, a handle, a burner having a tapered burner nozzle, 115 adapted to engage a seat in said iron, said locking means retaining said nozzle in a gas tight position upon its seat.

5. In a soldering tool, an iron provided with a mixing and combustion chamber and an end aperture connecting with the chamber, a conical seat around said aperture, a burner nozzle in the form of a truncated cone adapted to be seated in said aperture of the iron, air inlet ports in the iron leading to the 120 flame beyond the mouth of the nozzle, and a series of transverse exit ports of varying diameters leading to the combustion chamber.

6. In a soldering tool, an iron provided with a mixing and combustion chamber and 125

an end aperture connecting with the chamber, a conical seat around said aperture, a burner nozzle in the form of a truncated cone adapted to be seated in said aperture of the iron, and a plurality of air inlet ports angularly positioned with reference to the longitudinal axis of the iron and adapted to introduce air to a flame beyond the mouth of the burner nozzle.

10 7. In a soldering tool, a handle, a tapered sleeve removably fitted thereon, an iron provided with a combustion chamber, an aperture at one end thereof, a conical seat adjacent to said aperture, a burner provided with 15 a mixing chamber, said iron and burner having angularly positioned ports to the combustion and mixing chambers, respectively, a burner nozzle, and means for retaining the burner nozzle firmly in gas tight contact 20 with the conical seat formed in said iron, whereby the leakage of gas is prevented.

8. In a soldering tool, an interchangeable iron having a mixing and combustion chamber, an aperture at one end thereof, a seat formed within said aperture, a truncated cone shaped burner nozzle adapted to engage with said seat to form a gas tight joint, a plurality of transverse ports of varying diameters in the walls of said iron and communicating with said mixing and combustion chamber, the diameters of said ports decreasing toward one end of the iron, whereby increased combustion and greater heat is maintained in the iron, as set forth. 30

In testimony whereof, we affix our signatures, in presence of two witnesses.

LEONARD L. BIVENS.
GEORGE G. HUNTER.
